UNITED STATES PATENT OFFICE.

HENRY H. PORTER, JR., OF CHICAGO, ILLINOIS, ASSIGNOR TO SWANITZ COMPANY, OF CHICAGO, ILLINOIS, A CORPORATION OF DELAWARE.

RAILWAY TRANSFER APPARATUS.

SPECIFICATION forming part of Letters Patent No. 734,610, dated July 28, 1903.

Application filed March 5, 1902. Serial No. 96,758. (No model.)

To all whom it may concern:

Be it known that I, HENRY H. PORTER, Jr., a citizen of the United States of America, residing at Chicago, in the county of Cook and State of Illinois, have invented certain new and useful Improvements in Railway Transfer Apparatus, (Case No. 5,) of which the following is a specification.

The first of the objects of my present invention is the provision of a novel arrangement of railway transfer apparatus in which there is employed, in combination with a traction-floor and trolley-plate, located above the same, a rail-track connecting with said traction-floor and a trolley-wire connecting with said trolley-plate.

Another object of my present invention is the combination, with the device already enumerated, of means for facilitating the running of the truck from the traction-floor to the outside, and vice versa, and a protective covering for the traction-floor, from which is suspended the trolley-plate, within which are arranged suitable platforms which may be used in connection with the other apparatus.

In carrying out my invention I provide mechanism which I have illustrated in preferred form in the accompanying drawings, in which—

Figure 1 is a sectional perspective view illustrating my improvements, and Fig. 2 a sectional elevation of the same.

At 3 I have shown a traction-floor having a smooth upper surface and protected by a covering 4, from which is suspended a trolley-plate 5 in the manner shown. Within the protective covering I arrange, at each side thereof, a couple of platforms 6 and 7, adjacent to which upon the outside of the covering are disposed tracks 8 and 9, adapted to receive cars 10 for loading or unloading merchandise.

At some convenient point in the protective covering 4 there is provided an opening or door 11, from which there extends outwardly a rail-track 12, there being guide-blocks 13 provided where the rail-track joins the traction-floor 3.

To the trolley-plate 5 there is connected a trolley-wire 14, which extends out and over the track 12 as a means for supplying power

to motor-driven cars traveling upon said track, one of said cars being shown at 15, the same being provided with wheels which are constructed to run equally well upon the traction floor or track, as desired, and provided with a novel form of trolley 16, for instance, (see Fig. 2,) which has a wheel arranged to run equally well in contact with the trolley-plate or trolley-wire 14.

By the combination of devices above enumerated it is obvious that I have provided means whereby a merchandise-transfer truck can be used within a protective covering for the local transfer of goods from one point to another adjacent to either of the platforms 6 or 7 and whereby also, if desired, the same truck without unloading can be moved by the same power mechanism along the track 12 to any point desired—as, for example, another transfer-house, two of which so connected are indicated in Fig. 2.

Having thus described my invention, what I claim as new, and desire to secure by Letters Patent, is—

1. A railway transfer apparatus comprising in combination with an electrically-driven truck a traction-floor, a trolley-plate above said floor, a rail-track continuous with the floor, and a trolley-wire adjacent to said track.

2. A railway transfer apparatus comprising in combination with an electrically-driven truck a traction-floor, a trolley-plate above said floor, a rail-track connecting with said floor, and a trolley-wire adjacent to said rail-track, said trolley-wire connecting with said trolley-plate whereby to form a continuous conductor with the latter, substantially as described.

3. A railway transfer apparatus comprising in combination with an electrically-driven truck a traction-floor, a protective covering for said floor, a trolley-plate above said floor suspended from said protective covering, a rail-track extending outside said protective covering and connecting with said traction-floor, and a trolley-wire adjacent to said rail-track and connecting with said trolley-plate, substantially as described.

4. In railway transfer apparatus the combination of a covered traction-floor, a trolley-plate above said floor, a railway-track con-

tinuous with the floor and a trolley-wire parallel therewith connected with said trolley-plate, and a truck adapted to run at will either upon the floor or along said track, substantially as described.

5. In railway transfer apparatus the combination with a covered traction-floor, a trolley-plate above said floor, a railway-track and trolley-wire connected respectively with said

floor and said trolley-plate, and a truck provided with wheels adapted to run either upon the said floor or upon the said track and driven by a current from said trolley plate and wire.

HENRY H. PORTER, JR.
